UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

DISTRIBUTER FOR IGNITION DEVICES.

1,226,234.

Specification of Letters Patent.

Patented May 15, 1917.

Application filed September 15, 1916. Serial No. 120,326.

To all whom it may concern:

Be it known that I, CHARLES THOMAS MASON, a citizen of the United States, residing at Sumter, in the county of Sumter and

5 State of South Carolina, have invented certain new and useful Improvements in Distributers for Ignition Devices, of which the following is a specification, reference being had to the accompanying drawing.

10 The invention relates to new and useful improvements in distributers for ignition systems and more particularly to a distributer for high tension currents.

15 The invention is particularly useful in distributing in a simple and efficient manner high tension current to a plurality of translating devices such as the spark plugs in a gas engine.

20 In my prior application Serial Number 35,155, filed June 19th, 1916, I have shown, described and claimed a method and apparatus for generating and distributing electric current in connection with an ignition system for an internal combustion engine.

25 The present invention is an improvement on the distributing device shown therein.

An object of the invention is to provide a distributer for ignition systems of the above character wherein the central stem or trunk 30 conductor may be stationary and have continuous connection with a series of circularly disposed contacts which in turn are adapted to be connected at predetermined intervals with other contacts or terminals 35 leading to the translating devices.

A further object of the invention is to provide a distributer of the above character wherein the traveling contacts are so arranged as to be readily accessible for inspection 40 during the rotation of the distributer.

A still further object of the invention is to provide a distributer having three circular rows of contacts, the contacts of the central row being continuously connected to 45 each other and also to a trunk conductor receiving current from a source of supply, together with means for alternately connecting said central row of contacts to the respective outer rows of contacts which in turn are connected to the translating devices.

50 A still further object of the invention is to provide a distributer of the above character wherein the trunk conductor is sta-

tionary and connected by movable means with the central rows of contacts which 55 means makes continuous connection with at least two of the contacts.

These and other objects will in part be obvious and will in part be hereinafter more 60 fully disclosed.

In the drawings, which show by way of illustration one embodiment of the invention:—

Figure 1 is a view partly in section and partly in side elevation showing my improved distributer and a part of the current generating apparatus which may be used 65 in connection therewith;

Fig. 2 is a view in end elevation showing the distributer with the cap plate removed 70 and also showing a portion of the distributer broken away to expose the driving gears therefor;

Fig. 3 is a perspective view of the outer shell of a casing; and 75

Fig. 4 is a perspective view of the inner rotating part of the distributer.

My improved distributer is especially adapted to be used in connection with high tension currents for furnishing current to 80 translating devices such as the spark plugs of an internal combustion engine. The current supply may be received from any suitable source, although I have shown in the drawings a magneto or ignition dynamo for 85 generating the current which is of the well known "Dixie" type.

The current is received by a trunk conductor which is fixed against movement. The distributer consists of an outer casing 90 which is preferably cylindrical in form and an inner rotating part.

The outer casing is supplied with three circular rows of contacts or brushes, the inner rows of which are connected together while the outer rows are 95 connected to the respective translating devices or spark plugs. The rotating part carries a contact member which is connected continuously with the trunk conductor and this contact member is adapted to engage 100 simultaneously two or more of the contacts or brushes in the central row above referred to.

In this way current is continuously supplied to this central row of contacts. The inner rotating part also carries two 105 pairs of contacts, one contact of each pair

- is adapted to alternately engage the central row of brushes or contacts while the other contacts in said pairs coöperate respectively and alternately with the outer rows of 5 brushes or contacts connected with the translating devices. A cap plate secured to the casing covers the rotating part but this cap plate may be quickly removed for inspection purposes without in any way disturbing any 10 of the contacts.
- 10 Referring more in detail to the drawings, my improved distributor consists of an outer shell or casing 1, which as above noted, is cylindrical in form. This outer shell or casing 15 1 is carried by the frame of the magneto, which is indicated at 2. Suitably secured to this casing 1 is a bearing member 3 which is formed with a projecting sleeve 4. This sleeve is preferably integral with 20 the bearing member 3. Extending through the sleeve 4 is a bushing or support 5 of insulating material which has a central opening extending entirely therethrough and located in this central opening is a stem 25 or trunk conductor 6.
- 25 Said trunk conductor 6 carries a spring pressed contact 7 at its inner end which is adapted to make contact with the terminal of the secondary of a current generating 30 coil 8, when said distributor is used with a magneto. When used with another source of current this trunk conductor is connected to said source.
- 35 Located within the casing 1 is a rotating part or member 9 which is preferably made of insulating material the same as the casing 1 and this rotating part 9 is secured by suitable devices to a carrier 10 having a gear 40 11 which meshes with a gear 12 mounted on the shaft of the magneto. The distributor as shown in the drawings is designed for supplying current to a twelve cylinder gas engine, as will appear more fully hereinafter. When said distributor is used in 45 connection with a magneto having four E. M. F. peaks at each rotation, the magneto shaft is timed so as to rotate one and one-half times the engine speed and the gears 11 and 12 are so proportioned that the gear 50 11 will be driven at a speed ratio of one to three of the magneto shaft or one to two of the engine shaft. The carrier 10 is mounted on ball bearings 13 which are supported by the sleeve 4 above referred to.
- 55 The casing 1 is provided with a series of recesses or wells in which are mounted contact members or brushes. These contact members or brushes are arranged in three circular rows. In the outer row there are 60 brushes 13, 14, 15, 16, 17 and 18. In the middle row there are also six contact brushes or members, three of which are indicated at 19, 20 and 21, Fig. 3. This row of contacts are connected together as indicated by the 65 dotted line in Fig. 3. The inner row of con-

tacts or brushes are six in number and two of these are indicated at 22 and 23 in Fig. 3 of the drawings.

Individual cables 24, 25, 26, etc., are connected to the front row of contacts or 70 brushes 13, 14, 15, 16, 17 and 18, while individual cables 27, 28, 29 etc., are connected to the inner row of contacts or brushes 22 and 23. These cables may be connected to the contacts or brushes in any suitable manner and their outer ends are connected to the translating devices or spark plugs. 75

As above noted, all of the central row of brushes or contacts are electrically connected as indicated by the dotted lines and these 80 contacts are adapted to be engaged by a contact member 30 carried by the rotating part 9. Said contact member 30 is of sufficient length to make contact simultaneously with at least two of the contacts or 85 brushes of the central row. Said contact member 30 also extends radially of the rotating part 9 and is connected to a plate 31 against which a yielding contact 32 presses. This yielding contact is an extension of the 90 trunk conductor or stem 6. The trunk conductor or stem 6 is, therefore connected through this plate 31 and the contact 30 with the central row of contacts which are each connected together, thus forming a live 95 row of contacts.

A pair of contacts 33 and 34 is mounted on the rotating part 9, the contact 33 being in the same plane as the contact 30, as indicated by the broken line in Fig. 4. The 100 contact 33 is not, however, electrically connected with the contact 30.

This rotating part 9 carries a second pair of contacts 35 and 36 and the contact 35 is in the same plane as the contact 30. The 105 contact 34 is located at the inner side of this central plane containing the contacts 33, 30 and 35 while the contact 36 is located at the outer side of this plane. In other words, the contact 34 is so disposed as to coöperate 110 with the contacts or brushes in the inner row carried by the outer casing while the contact 36 is so located as to coöperate with the contacts or brushes in the outer row carried by the casing. The pairs of contacts 115 are also so disposed that they are alternately in engagement with the contacts or brushes carried by the casing. In other words, when the contacts 35 and 36 are in engagement with the pair of contacts or brushes on the 120 casing then the contacts 33 and 34 are midway between the contacts or brushes as indicated at X, in Fig. 3 of the drawings.

The contacts or brushes in the outer rows may be of any desired construction and are 125 preferably yieldingly mounted with some suitable means for limiting the outward movement thereof so that these contacts or brushes are free from engagement with the outer face of the rotating part 9 but make 130

engagement with the contacts carried thereby.

- It is thought that the operation of my improved distributor will be obvious from the above description. A suitable source of current supply is connected with the trunk conductor and the inner rotating part is geared to the engine shaft by a suitable train of mechanism so that it is rotated at a speed 10 ratio of one to two of the engine shaft. As this inner part 9 rotates the contact 30 will be continuously in engagement with the central row of contacts as it is of sufficient length to engage at least two of these contacts and inasmuch as all the contacts are 15 connected, each contact becomes a live conductor. The pair of contacts 33 and 34 will join one of the contacts in the central row to one of the contacts in the inner row and 20 this furnishes current to the connected translating device or spark plug. At the same time the contacts 35 and 36 are out of engagement with the central row of contacts and the outer row of contacts.
- 25 When the rotating part 9 turns through a certain angle then the contacts 33 and 34 will move away from engagement with the contacts or brushes and the contacts 35 and 36 will be brought into engagement with a 30 contact or brush in the central row and a contact or brush in the outer row and as these contacts 35 and 36 are electrically connected current will then be furnished to the translating device or spark plug connected to the brush or contact engaged by the contact 36. 35 As this part 9 continues its rotation it will be apparent that first a contact or brush in one row will be electrically connected to the central row of contacts or brushes and then a 40 contact or brush in the other row will be connected thereto and, therefore, these pairs of contacts on the rotating part 9 engage alternately the respective inner and outer rows of contacts and when said rotating part 9 has 45 made a complete rotation each one of the individual cables will have been electrically connected with the source of supply.
- Attached to the casing 1 by any suitable means is a cap plate 37 of insulating material and this cap plate may be removed 50 without disturbing the contacts or brushes and when removed it will be apparent that the contacts or brushes are open to inspection while the distributor is running.
- 55 Particular attention is called to the fact that the trunk conductor or stem 6 is stationary and makes contact with the rotating part substantially at its axis of rotation so that there is little or no wear between these 60 parts. This is accomplished by passing the trunk conductor through the bearing sleeve for the gear which operates the rotating part, and the mounting and supporting of the rotating part on the gear or carrier 65 therefor.

Furthermore, it will be noted that the rotating part 9 is mounted on a ball bearing which is supported by a sleeve formed integral with the frame of the machine.

Again, it will be noted that the high tension current circuit is broken at two places, namely, between the central row of contacts or brushes and the contacts on the rotating part which coöperate therewith and also between the brushes or contacts connected with the translating devices and the respective contacts on the rotating part which coöperate therewith. In other words, there are always two gaps made in the secondary high tension circuit when it is broken.

It is obvious that minor changes in the details of construction and arrangement of parts may be made without departing from the spirit of the invention as set forth in the appended claims.

Having thus described my invention, what I claim as new and desire to secure by Letters Patent, is:

1. A distributor for ignition systems including in combination a trunk conductor adapted to be connected with a source of current, a casing having a plurality of contacts arranged in circular rows, means for connecting the contacts in one of said rows together and to the trunk conductor, cables connected with the remaining rows of contacts and adapted to be connected to translating devices, a plurality of pairs of traveling connected contacts arranged so that one contact of each pair will engage alternately the contacts connected to the trunk conductor while the other contacts of each pair engage respectively and alternately the contacts connected to the translating devices.

2. A distributor for ignition systems including in combination a trunk conductor adapted to be connected with a source of current, a casing having a plurality of contacts arranged in circular rows, means for connecting the contacts in one of said rows together and to the trunk conductor, cables connected with the remaining rows of contacts and adapted to be connected to translating devices, a rotating part located within said casing and having a plurality of pairs of traveling connected contacts arranged so that one contact of each pair will engage alternately the contacts connected to the trunk conductor while the other contacts of each pair engage respectively and alternately the contacts connected with the translating devices.

3. A distributor for ignition systems including in combination a trunk conductor adapted to be connected with a source of current, a casing having a plurality of contacts arranged in circular rows, means for connecting the contacts in one of said rows together and to the trunk conductor, cables

- connected with the remaining rows of contacts and adapted to be connected to translating devices, a rotating part located within said casing and having a plurality of pairs of traveling connected contacts arranged so that one contact of each pair will engage alternately the contacts connected to the trunk conductor while the other contacts of each pair engage respectively and alternately the contacts connected with the translating devices, a cap plate connected to said casing closing the end thereof and covering said rotating part.

4. A distributor for ignition systems including in combination a trunk conductor adapted to be connected with a source of current, a casing having a plurality of contacts arranged in three circular rows, a rotating part located within said casing, means for connecting the central row of said contacts, means carried by the rotating part for connecting said central row of contacts to the trunk conductor, a plurality of pairs of contacts carried by said rotating part and arranged so that one contact of each pair will engage the central row of contacts on the casing while the other contacts of each pair engage respectively and alternately the contacts on said casing.

5. A distributor including in combination a bearing sleeve, a bushing of insulating material extending through said sleeve, a trunk conductor extending through said bushing and having a yielding contact at its outer end, a part mounted to rotate upon said sleeve, a plate located centrally of the rotating part and adapted to be engaged by said yielding contact, a contact carried by the outer face of said rotating part electrically connected with said plate, an outer casing surrounding said rotating part, a plurality of circular rows of brushes carried by the outer casing and normally projecting slightly beyond the inner face thereof, means for connecting the brushes of the central row, cables connected to the brushes of the outer rows and adapted to be connected with translating devices respectively, said central row of brushes being adapted to engage the contact member on the rotating part whereby said brushes are continuously connected with the trunk conductor, pairs of contacts carried by the rotating part and disposed so that one contact in each pair is adapted to engage alternately the brushes in the central row, while the other contacts of each pair engage respectively and alternately the brushes in the outer rows.

6. A distributor for ignition systems including in combination a bearing sleeve, a rotating part, an operating gear connected thereto, ball bearings for supporting said gear and rotating part on said sleeve, a trunk conductor extending centrally through said

sleeve, a contact carried by the rotating part and continuously connected with said trunk conductor, an outer casing, a plurality of circular rows of brushes carried by the outer casing and disposed so that the central row thereof is connected with said contact on the rotating part, means for connecting the central row of brushes with each other, pairs of contacts carried by said rotating part and arranged so that one contact of each pair is adapted to alternately engage the brushes in the central row while the other contacts of said pairs respectively and alternately engage brushes in the outer rows.

7. A distributor for ignition systems including in combination a bearing sleeve, a rotating part, an operating gear connected thereto, ball bearings for supporting said gear and rotating part on said sleeve, a trunk conductor extending centrally through said sleeve, a contact carried by the rotating part and continuously connected with said trunk conductor, an outer casing, a plurality of circular rows of brushes carried by the outer casing and disposed so that the central row thereof is connected with said contact on the rotating part, means for connecting the central row of brushes with each other, pairs of contacts carried by said rotating part and arranged so that one contact of each pair is adapted to alternately engage the brushes in the central row while the other contacts of said pairs respectively and alternately engage brushes in the outer rows.

8. A distributor for ignition systems including in combination a supporting sleeve, a bushing extending therethrough, a trunk conductor extending through the bushing and having a yielding contact member at its outer end, a rotating part having a contact on its outer face, a plate located centrally of said rotating part against which said yielding contact bears, said plate being connected to the contact on the outer face of the rotating part and devices cooperating with said contact on the outer face of the rotating part for distributing the current from the trunk conductor to the plurality of translating devices.

9. A distributor for ignition systems including in combination an inner rotating part, an outer casing, a plurality of circular rows of brushes carried by said outer casing, means for connecting the central row of brushes, a trunk conductor, means for connecting said trunk conductor to said central row of brushes, pairs of contacts carried by said rotating part, said pairs of contacts being so disposed that one contact of each pair engages alternately the brushes in the central row while the other contacts of said

pairs engage alternately and respectively the brushes in the outer rows.

10. A distributer for ignition systems including in combination a rotating part and 5 a fixed part, one of said parts having a plurality of rows of brushes, means for connecting the brushes in one of said rows, the other part having two pairs of contacts, said

pairs of contacts being so disposed that one contact in each pair engages alternately the 10 connected brushes while the other contacts of said pairs engage alternately and respectively the brushes of the other rows.

In testimony whereof I hereunto affix my signature.

CHARLES THOMAS MASON.
